US0D1063189S

(12) **United States Design Patent** (10) Patent No.: **US D1,063,189 S**
(45) Date of Patent: ** Feb. 18, 2025

(54) **ELECTRONIC CIGARETTE**

(71) Applicant: **SHENZHEN WOODY VAPES TECHNOLOGY CO., LTD.**, Shenzhen (CN)

(72) Inventors: **Xing Peng**, Shenzhen (CN); **Bozhong Li**, Shenzhen (CN)

(**) Term: **15 Years**

(21) Appl. No.: **35/519,362**

(22) Filed: **Nov. 1, 2023**

(80) **Hague Agreement Data**

Int. Filing Date: **Nov. 1, 2023**

Int. Reg. No.: **DM/233603**

Int. Reg. Date: **Nov. 1, 2023**

Int. Reg. Pub. Date: **Dec. 15, 2023**

(30) **Foreign Application Priority Data**

Aug. 18, 2023 (CN) 202330530881.8

(51) **LOC (15) Cl.** **27-07**

(52) **U.S. Cl.**

USPC **D27/162**

(57) **CLAIM**

The ornamental design for an electronic cigarette as shown and described.

DESCRIPTION

1. Electronic cigarette

1.1 : Front

1.2 : Rear

1.3 : Left

1.4 : Right

1.5 : Top

1.6 : Bottom

1.7 : Perspective

1.8 : Perspective

1.1 is a front view of an electronic cigarette showing our new design; 1.2 is a rear view thereof; 1.3 is a left view thereof; 1.4 is a right view thereof; 1.5 is a top view thereof; 1.6 is a bottom view thereof; 1.7 is a perspective view thereof; and 1.8 is another perspective view thereof.

1 Claim, 7 Drawing Sheets
